UNITED STATES PATENT OFFICE.

EDWARD F. SMITH, OF ROCHESTER, NEW YORK, ASSIGNOR TO JOSIAH ANSTICE, OF ROCHESTER, NEW YORK.

SLICING-MACHINE.

No. 830,935.

Specification of Letters Patent.

Patented Sept. 11, 1906.

Application filed August 8, 1904. Serial No. 220,045.

To all whom it may concern:

Be it known that I, EDWARD F. SMITH, a citizen of the United States, residing at Rochester, in the county of Monroe and State of New York, have invented certain new and useful Improvements in Slicing-Machines, of which the following is a specification, reference being had therein to the accompanying drawings.

This invention relates to improvements in slicing-machines, which is more especially intended for slicing meats, though it may be used for slicing other substances.

In the accompanying drawings, Figure 1 is a side elevation of a machine embodying my invention looking at the same from the handle or operator's side. Fig. 2 is a similar view looking at the machine from the opposite side. Fig. 3 is a view similar to Fig. 1 with the cutting mechanism shown in position after a slice has been cut and after the cutter has traveled across the end of the holder, whereas in Fig. 1 the cutting mechanism is shown in the position for beginning the slicing movement across the end of the holder. Fig. 4 is a detached perspective view of the oscillating member or frame which carries the revolving cutter and the gage-plate; the crank and link for oscillating the same being also shown. Fig. 5 is a top plan view of the machine, a portion of the holder being broken away. Fig. 6 is a sectional view taken on the line 6 6 of Fig. 1 looking in the direction indicated by arrow. Fig. 7 is a sectional view on the line 7 7 of Fig. 1 looking in the direction indicated by arrow. Fig. 8 is a detached longitudinal sectional view of the holder and feeder.

Referring now to the accompanying drawings, 11 indicate two vertical standards arranged practically in alinement, and these standards are connected by a web or frame-piece 2. The standards and the web or connection 2 serve to support all the mechanism with the exception of the driving-shaft and its gears, the latter being supported by a standard 3.

Supported in a horizontal bearing 4 is a horizontal shaft 5. Secured to the inner projecting end of the shaft 5 by means of a suitable member or screw 6 is the collar 7 of the oscillating member or frame 8, the said collar forming, in effect, a portion of the oscillating member. Revolubly mounted upon an arm

or extension 9 of the oscillating member is a cutter 10. Attached to the cutter 10 is a gear 11, and this gear 11 is in mesh with a gear 12, which is mounted concentrically with the axis of the oscillating member or frame, and in operation acts as a transmission or idler-gear. Connected with the gear 12 is a pinion 14, and this pinion 14 in turn meshes with a gear 15.

Mounted in a horizontal bearing 16 is a driving-shaft 17, to which a handle or driving member 18 is attached for driving it. This shaft carries a pinion or gear 19, which is in mesh with, preferably, an internal gear 20, which is rigidly and concentrically connected with the gear 15.

The oscillating member 8 also carries an arm 21, to which is attached a transversely-adjustable gage-plate 22, which extends in a plane parallel with the cutting-face of the revoluble cutter 10 and located at a point in advance of the cutter and adapted to be adjusted transversely in relation to the cutter for varying the thickness of the slice to be cut. This adjustment is accomplished by means of a thumb-screw 23, which passes through a screw-threaded stud 24, extending from a lateral arm 25, to which the gage-plate 22 is attached.

A laterally-extending trough or holder support 26 is suitably supported by the standards and connecting-piece, and located at the inner end of this support-trough is a substantially rectangular wall or frame 27, through which the meat or substance to be cut will extend. Located within and supported by the support or trough in any suitable manner is a traveling meat or substance holder or feeder 28, which is angular in cross-section and carries at its inner end a plurality of points 29 for the purpose of engaging and thereby firmly holding the meat to be cut. Adjustably arranged on the holder or carrier 28 is a clamping member 30, carrying at its upper end a transversely-arranged arm 31, provided with pins 32 for engaging the meat. This clamp 30 is movable up and down to accommodate and clamp pieces of meat of various sizes and is held in its adjusted position through the medium of a thumb-screw 33, the member 30 having a longitudinal slot 34, through which the stem of the clamping-screw passes. The carrier 28 is normally drawn inward by means of a tape 35, con-

nected with a spring-actuated pulley 36. The construction of such pulleys being so well understood that detailed illustration or description thereof is unnecessary.

5 The gear 15 is rigidly attached to one end of the shaft 37, and to the other end of this shaft is rigidly attached a crank-arm 38. A link 39 connects the outer end of the crank-arm 38 with the oscillating member 8 at the point 40, so that as the shaft 37 is revolved the member 8 is oscillated and the cutter 10 and gage-plate 22 are moved back and forth across the inner end of the trough which carries the meat holder and feeder.

15 In operation the meat to be sliced is placed in the carrier 28 and clamped therein with its end projecting inwardly beyond the inner end of the carrier 28. The carrier being held normally inward causes the inner end of the 20 meat to rest against the gage-plate 22. The operator then causes the drive-shaft 17 to be revolved, and this causes the cutter to be carried across the end of the meat and to cut a slice of the thickness regulated by the position of the gage-plate. This movement through the gearing causes the cutter to be revolved as it moves across the trough, which greatly facilitates the ease of operation and greatly improves the character of the work.

30 The principal feature of the present invention is the combined oscillating and revolving cutter, and since the specific means by which this result is accomplished may be varied I do not limit myself to the particular mechanism herein shown beyond the generic principles therein involved.

Having thus described my invention, what I claim, and desire to secure by Letters Patent, is—

40 1. A slicer comprising a holder, a pivoted arm adapted to reciprocate in a direction across said holder, a revolute cutter journaled in the free end of the arm, a gear attached to the cutter, a gear journaled concentrically with the pivot of said arm and in mesh with said cutter-gear, the last-mentioned gear provided with a concentric pinion, a gear 15 in mesh with the pinion, a crank-and-link connection between said gear 15 and said reciprocating arm, and a driving-shaft geared to said gear 15, substantially as described.

2. A slicer, comprising a holder, a pivoted arm adapted to be reciprocated in a direction across the holder, a revolute cutter journaled in the free end of said arm, the cutter having a concentric gear attached thereto, a gear journaled concentrically with the pivot of said arm, a driving-gear meshing with the last-mentioned gear, a pivoted gage-plate extending across the end of said holder, a crank-and-link connection between said drive-

gear and the arm, and a crank connected between said intermediate gear and the pivoted gage.

3. A slicer, comprising a holder, a pivoted arm adapted to reciprocate in a direction across said holder, a revolute cutter journaled in the free end of said arm, the cutter having a concentric gear attached thereto, an idle gear concentric with the pivot of said reciprocating arm and in mesh with said cutter-gear, a large gear concentric with the idle gear and meshing with the opposite side thereof, and means carried by the large gear for reciprocating said arm and rotating said gear and means for rotating said large gear.

4. A slicer, comprising a holder, a pivoted arm adapted to reciprocate in a direction across said holder, a revolute cutter journaled in the free end of said arm, the cutter having a concentric gear attached thereto, an idle gear concentric with the pivot of the reciprocating arm and in mesh with the cutter-gear, a large gear in mesh with the opposite side of 85 the idle gear and means carried by the large gear for reciprocating said arm and rotating said gear and means for rotating said large gear.

5. A slicer, comprising a holder, a pivoted arm adapted to reciprocate in a direction across said holder, a revolute cutter journaled in the free end of said arm, the cutter having a concentric gear attached thereto, an idle gear concentric with the pivot of said reciprocating arm and in mesh therewith, a large gear meshing with the opposite side of said idle gear, and having internal teeth, a drive-pinion meshing with the internal teeth, a crank carried by said pinion, a crank-and-link connection between said large gear and said arm.

6. A slicer, comprising a holder, a pivoted arm adapted to reciprocate in a direction across said holder, a revolute cutter journaled in the free end of said arm, the cutter having a concentric gear attached thereto, an idle gear concentric with the pivot of said reciprocating arm and in mesh with the gear carried by the knife, a large gear meshing with the opposite side of said idle gear and having internal teeth, a drive-pinion meshing with the internal teeth, an operating-crank carried by the pinion, the crank-arm carried by said large gear and a link connected between the crank-arm and the knife-carrying arm, whereby the knife is reciprocated and simultaneously rotated.

In testimony whereof I affix my signature in presence of two witnesses.

EDWARD F. SMITH.
